UNITED STATES PATENT OFFICE.

JULIUS H. HIRSHBERG, OF OAKLAND, CALIFORNIA.

ELECTRICALLY-CONTROLLED SYSTEM FOR MOVING-PICTURE THEATERS.

1,160,714.

Specification of Letters Patent.

Patented Nov. 16, 1915.

Application filed October 2, 1911. Serial No. 652,241.

To all whom it may concern:

Be it known that I, JULIUS H. HIRSHBERG, a citizen of the United States, residing at Oakland, in the county of Alameda and State of California, have invented certain new and useful Improvements in Electrically-Controlled Systems for Moving-Picture Theaters, of which the following is a specification.

10 The present invention relates to an automatically operated electrically controlled system for moving picture theaters.

In accordance with my invention the moving picture machine is operated without the aid of an attendant and after the picture is shown the machine is stopped and other instrumentalities set in operation, such as a graphophone and a dissolving stereopticon. After these have operated for a suitable 20 length of time they are stopped and the moving picture machine put in operation again to show the next picture. After this picture has been shown, the moving picture machine is stopped and the lights turned on

25 and a piano or other instrument operated, for intermission. The entire system operates without the aid of human agency.

An important object of the present invention is to provide a system of the above mentioned character, which is automatic in operation, reliable and not subject to derangements.

Other objects and advantages of the present invention will be apparent during the 35 course of the following description.

In the accompanying drawings forming a part of this specification and in which like numerals are employed to designate like parts throughout the same, Figure 1 is a 40 diagrammatic view of the system, showing the various circuits, and, Fig. 2 is a plan view of a clock mechanism included in the system.

In the drawings wherein is illustrated a 45 preferred embodiment of my invention, the numeral 1 designates a brass disk forming a portion of the clock dial and about the disk 1 is a ring 2 of fiber. The fiber ring 2 is provided upon one side with numerals running 50 from one to twelve to designate the p. m. hours and provided upon its opposite side with numerals running from one to twelve to designate the a. m. hours, as shown. Surrounding the fiber ring 2 is a brass ring

3, to which are attached pins 4 carrying numerals which run from one to twenty-four, to designate all the hours of the day.

The numeral 5 designates an hour hand and the numeral 6 a minute hand. The hand 5 travels the distance between two 60 hour marks while the hand 6 makes a complete revolution of the disk. Any suitable mechanism may be employed to move the hands 5 and 6, preferably that found in the ordinary electrically operated clock.

65 My system may be employed to operate a moving picture theater during every hour of the day or during any selected hour or hours. Disposed between the hour marks are contacts 7, 8 and 9, which are insulated from the brass ring 3 and from each other. These contacts are held stationary by any suitable means. The hour hand 5 may preferably be provided with a platinum tip or point 10, which makes contact with the contacts 7 to 9. The hour hand 5 is insulated from the hand 6, disk 1 and associated elements.

70 The numeral 11 designates a source of current, having one pole thereof connected with the hour hand 5 by a wire 12. The other pole of this source of current is connected with a common wire 13, with which are connected wires 14, 15 and 16. Each of the wires 14, 15 and 16 have electro-magnets 17 75 of a relay connected in series therewith, as shown. The wires 14, 15 and 16 extend upwardly beyond these relays and are horizontally disposed in parallel relation, the wire 16 being uppermost, the wire 14 intermediate, and the wire 15 lowermost, as shown. The segments 7 are connected with the wire 15 by wires 18, the segments 8 are connected with the wire 16 by wires 19 and the segments 9 are connected with the wire 14 by 85 wires 20.

80 The numerals 21 and 22 designate main feed wires having connection with wires 23 and 24, respectively. The flow of current through wires 23 and 24 is controlled by a 100 manually operated switch 25. The relays comprise inverted substantially U-shaped armatures 26, adapted to engage contacts 27, 28, 29, 30, 31 and 32, when the electro-magnets 17 are energized. Connected with the 105 wire 24 are wires 33, 34 and 35, connected respectively with the contacts 28, 30 and 32, as shown. Connected with the contacts 27,

29 and 31, are wires 36, 37 and 38, respectively. The wires 37 and 38 are connected with the wire 23. Connected in parallel between the wires 23 and 36 are a suitable number of electric lamps 39, such as incandescent lamps. An electrically operated piano 40 or other musical instrument is also connected in parallel between these wires. Connected in series with the wire 34 is a 10 motor 41 for operating the moving picture machine and an automatic arc lamp 42 comprised in said machine. Connected in series with the wire 35 is a motor 43 to operate means which move the slides of a dissolving 15 stereopticon.

The numeral 44 designates automatic arc lamps of the dissolving stereopticon, which lamps are connected in series with the wire 35. The motor 43 may be employed to operate 20 means for turning off and on the arc lamps 44, as is customary in causing the picture to fade away while another is being thrown on the canvas.

The operation of the system is as follows:—Assuming that the system is designed to operate between seven and eight p. m., when the hour hand 5 is moved into engagement with the contact 7, a circuit will be closed and current will flow from one side 25 of the source of current 11, through wire 12, hand 5, contact 7, wire 18, wire 15, electro-magnets 17 in series therewith, and through wire 13 back to the source of current. The electro-magnets 17 thus become energized 30 and draw the armature 26 downwardly to engage contacts 29 and 30. This engagement continues as long as the hand 5 engages the segment 7, which depends of course, upon the width of said contact 7. 35 Current will now flow from the main wire 22 through wire 24, wire 34, motor 41, and arc lamp 42 connected in series therewith, through contact 30, armature 26, contact 29, wire 37 and through the wire 23 back to the 40 wire 21. The motor 41 is thus set in operation to operate the moving picture machine including the arc lamp 42, which is now lighted. When the hand 5 disengages the contact 7 the last referred to circuit is opened and 45 the hand 5 engages contact 8 to close a new circuit. In this circuit current will flow from one side of the source of current 11, through wire 12, hand 5, segment 8, wire 19, wire 16, electro-magnets 17 of the lowermost relay, 50 and through wire 18, back to the source of current 11. The electro-magnets 17 are now energized and draw the armature 26 down to engage contacts 31 and 32. The current will now flow from the main wire 22, 55 through wire 24, wire 35 and motor 43 and arc lamps 44 connected in series therewith, contact 32, armature 26, contact 31, wire 38, and through wire 23 back to wire 21. The motor 43 is thus set in operation to drive 60 the dissolving stereopticon, comprising the 65

arc lamps 44. A person may now sing to accompany the slide pictures or the motor 43 may be employed to drive a graphophone operating synchronously with the dissolving stereopticon. When the hand 5 travels off of the contact 8, the last named circuit is opened and the motor 43 stopped and the arc lamps 44 put out. The hand 5 now engages the next segment 7 whereby circuits are closed for again operating the motor 41 for driving 70 the moving picture machine. When the hand 5 disengages contact 7 the same subsequently engages contact 9 and a circuit is closed to energize the uppermost relay. In this circuit current flows from one side of the source of current 11, through wire 12, hand 5, segment 9, wire 20, wire 14, electro-magnets 17, and through wire 13 back to the opposite pole of the source of current. The armature 26 is now engaging contacts 27 and 28, 75 whereby current will flow from wire 22, through wire 24, wire 33, contact 28, armature 26, contact 27, wire 36, lamps 39 and piano 40, and through the wire 23 back to the wire 21. The lights 39 will now be 80 lighted for intermission, and the automatic piano 40 or other musical instrument set in operation. The operation is continued during all or selected hours.

I wish it understood that the form of my 85 invention herewith shown and described is to be taken as a preferred example of the same and that certain changes in the shape, size, and arrangement of parts may be resorted to without departing from the spirit 100 of the invention or the scope of the subjoined claims.

Having thus described my invention, I 105 claim:—

1. In an electrically operated system for theaters, a plurality of insulated stationary contacts, a movable contact arm to travel in engagement with the contacts to close circuits, a source of current having one pole connected with the contact arm, a feed wire 110 connected with the opposite pole of the source of current, a plurality of branch wires connected with the feed wire and connected with the stationary contacts, relays connected in the branch wires, main feed and return wires, main branch wires connected across the main feed and return wires and having circuits through them opened and closed by the relays, and translating devices connected in each of the main branch wires. 115 120

2. In an electrically operated system for theaters, a plurality of sets of stationary contacts of different widths for providing different periods of contact, a movable contact arm to travel in engagement with the contacts, a source of current having one pole connected with the contact arm, a feed wire connected with the opposite pole of the source of current, a plurality of branch wires connected with the feed wire and connected 125 130

with the sets of stationary contacts, relays connected in the branch wires, main feed and return wires, main branch wires adapted to be connected across the main feed and 5 return wires, translating devices connecting one main branch wire with the main return wire, means associated with the main branch wires whereby circuits are opened and closed through them by the relays, and other trans-

lating devices connected in one of the main 10 branch wires.

In testimony whereof I affix my signature in presence of two witnesses.

JULIUS H. HIRSHBERG.
